Application May 23, 1939, Serial No. 275,591

3 Claims. (Cl. 26—3)

My invention relates to methods of and means for singeing cloth, including a burner mechanism adapted to be used for such purpose.

The ends of the individual frayed-out fibers making up woven cloth are usually referred to collectively as "fuzz" by the textile mills. This fuzz must be removed at a suitable stage in the production of the finished cloth, a conventional manner of treatment being singeing. Two types of burners have been used in the past, each associated with the use of a particular process of singeing. One type of burner has an open flame, and the cloth merely travels in contact with the open flame. Another type of burner is the so-called compression flame type, more efficient in some respects than the open flame type of burner, but having disadvantages of its own. Among the disadvantages of the compression flame type of burner is the difficulty of adjustment when going from a heavy cloth to a light cloth, and vice versa, manifesting itself in poor singeing results in the case of heavy cloth or burning holes in the case of light cloth. Further disadvantages flow from the necessary arrangement of the burner. Among these disadvantages are the fact that the flame is diluted by relatively cool burned gases, and, because of the closed area in which the burning takes place, there is insufficient oxygen to cause complete burning of the fuzz. Because of the absence of oxygen, some of the burning occurs after the cloth leaves the burner, and the burning must result from residual heat retained by the cloth, thereby bringing about a condition, which cannot readily be controlled, across the entire cloth. These various disadvantages result in uneven singeing. There is moreover a pronounced tendency for the burner orifices to clog with incompletely burned particles of fuzz.

The principal object of my invention is the singeing of cloth by the use of methods and means which avoid the disadvantages of the character discussed hereinabove.

A further object is to singe cloth through the utilization of relatively low gravity fuel in such a manner as to avoid the fire and explosion hazards which have attended cloth singeing so frequently in the past.

A further object is the provision of a burner mechanism particularly adapted for burning premixed oil air and oil vapor but utilizable to advantage in burning any premixed combustible fuel of a fluid type.

A still further object is to improve the quality

of singeing while decreasing the time usually given over to this operation.

A still further object is to provide a method of and means for singeing cloth which is applicable to substantially equal advantage to any type of cloth to which singeing operations are usually applied.

In carrying out my invention, I pass the cloth in contact with the flame tips produced by means of a flame retention type of burner, preferably burning premixed air and oil vapors, the oil being vaporized preferably by using the method and general apparatus described in my issued Patents Nos. 2,122,684 and 2,123,887. The flame is caused to impinge the rapidly traveling cloth at such an angle that the major portion of burned gases follow the cloth counter-current to the direction of movement thereof. Associated with the burner mechanism and in advance of the burner, considering the direction that the cloth moves, I provide means for producing radiant heat, this means being, for example, a layer of refractory material which is heated by the hot products of combustion passing into contact therewith. The entire burner mechanism is positioned away from the cloth a sufficient distance to permit the spent gases to pass at relatively high velocity at the sides as well as at the ends of the burner mechanism, but sufficiently close to the cloth that air is not admitted except as desired and as controlled by the mechanism involved. As a consequence, the area between the radiant heating surface and the cloth is substantially free of oxygen except for the small amount which may be trapped within the interstices of the cloth. At the side of the burner opposite that at which the radiant heating surface is placed, air in controlled amounts is inspirited and engages the cloth very close to the flame propagated by the flame retention burner so as positively to control the burning action and remove fuzz from the interstices as well as from the surface of the cloth without endangering the woven fabric itself. The air is inspirited in large part at least by the movement of the cloth so that the proportion of air admitted is generally proportional to the speed of the cloth and, therefore, proportional to the demand.

In constructing the burner mechanism, I provide burner orifices in the form of obliquely or diagonally disposed slits so that each section of cloth passes at least two flame sections. The burner flame guards for obtaining the flame retention character, the refractory for producing radiant heat, and the air inspiriting mechanism

are all produced as a single unit with which the various functions and details of the method are carried out by even the relatively unskilled worker in the textile plant. The burner, however, including the various parts referred to, is produced in a plurality of sections of standard length or width so arranged that they may be secured together to produce a burner mechanism of any suitable length which may be constructed as a multiple of the smaller burner sections. Between the burner sections, I preferably mount sealing partitions, which function as gaskets as well as separators, to produce a plurality of manifold areas within the hollow space defined by the burner castings, these manifold areas being individual to the various burner sections. By supplying each one of these individual manifold sections with combustible mixture at definite manifold pressure, uniform flame quality and quantity is maintained entirely across the entire singeing apparatus. I may, of course, provide a continuous manifold and use other means to assure uniform flame conditions.

Since the burner of my invention is primarily intended for operation with vaporizable liquid fuel, and, since singeing operations generally require immediate starting and immediate stopping to produce uniform results, I extend a double steam line, comprising a steam delivery pipe and return pipe, through all of the manifold areas of the individual burner sections, these steam pipes extending through closely fitting apertures in the sealing partitions. By this means, the entire burner assembly may be kept warm with the result that, when the fuel vapor is first delivered to the burners, there will be little or no condensation such as would otherwise decrease the proportion of fuel to air and thereby lean out the flame and produce poor singeing and tend to burn the cloth. Furthermore, when a temporary stoppage is necessary, the steam lines will retain heat in the burner to prevent condensation of vapor within the burner itself, and thereby permit immediate starting when required. It may be noted that the heat delivered by the steam lines is not lost to any appreciable extent, but is picked up by the combustible mixture as it passes through, and, by keeping the burner warm, its efficiency is raised.

The efficiency of the entire installation is further increased by the use of the radiant refractory which absorbs heat from the spent gases. In connection with the use of steam, I wish to point out also that with my present invention I may also provide means not herein shown for immediately blanketing the area between the refractory and burner on the one side and cloth on the other with dry steam which will absolutely prevent injury to the cloth if it should be necessary to stop the cloth as it is passing over the burner. In this connection also, because of the advisability of being able to start and stop quickly, I may, in the same system, utilize spark plugs or other means for immediately igniting the burner as an incident in starting the movement of the cloth. While these features are not shown in the present invention, referring to them brings out with greater clarity the facility with which my present invention adapts itself to all of the problems usually found to exist in connection with the singeing of cloth in textile establishments.

Other specific objects and features of the invention will be apparent from a consideration of the following description taken with the accom-

panying drawings showing a preferred embodiment of my invention, wherein

Fig. 1 is an elevational view, looking at one side of a burner, comprising a plurality of segments, which is constructed in accordance with my invention. This view is broken away to conserve space and is shown partly in section to more clearly bring out the relationship of the parts;

Fig. 2 is a plan view such as would be seen when the burner is mounted for the cloth to travel above it, this view also being broken away to conserve space and having some parts removed in some of the sections to more clearly show the relationship of the parts;

Fig. 3 is a sectional view, partly in elevation, taken on the line 3—3 of Fig. 1 looking in the direction of the arrows, a section of cloth with the cloth guides in position being shown to illustrate a preferred manner of positioning the burner with respect to the moving cloth;

Fig. 4 is an enlarged sectional view taken on the line 4—4 of Fig. 2 looking in the direction of the arrows, the figure being a fragmentary vertical section taken through the end of the composite burner which is formed of a plurality of sections; (the section is also along the line 4—4 of Fig. 6).

Fig. 5 is an end elevational view, partly in section, such as would be seen by looking along the line 5—5 of Fig. 1;

Fig. 6 is an enlarged fragmentary plan sectional view, partly in elevation, taken along the line 6—6 of Fig. 4, looking in the direction of the arrows;

Fig. 7 is an enlarged fragmentary sectional view taken on the line 7—7 of Fig. 6, showing the specific construction of the flame guards and the manner in which the flame guards are attached to the burner casting. The view also indicates on a larger scale the relative position of the cloth, burner and inspirating means;

Fig. 8 is an enlarged fragmentary perspective view, partly broken away to illustrate the manner in which the burner grating parts are assembled with the burner main casting;

Fig. 9 is a sectional view taken on the line 9—9 of Fig. 1, looking in the direction of the arrows and showing the separating partition and ends of the individual flame guards in order to illustrate the manner in which the various burner sections are secured together;

Fig. 10 is a sectional view taken on the line 10—10 of Fig. 9 showing the sealing partitions between the sections in section and illustrating the manner in which the heat and steam pipes are carried through the sealing partitions;

Fig. 11 is a perspective view of the main burner casting individual to each section;

Fig. 12 is a perspective view of the sealing partition;

Fig. 13 is a perspective view of one of the flame guards; and

Fig. 14 is a perspective view of the air inspiration plate which is mounted to one of the flame guards.

The singeing burner mechanism of the present invention, as previously brought out, preferably is composed of a plurality of sections so arranged that they may be mounted together to produce a burner of suitable length. Certain of the parts are individual to each section, and certain parts are common to all of the sections. For convenience in bringing out the relationship of the parts, I shall first refer to the main burner cast-

ing, as shown in Fig. 11, as constituting the main part of one of the sections.

Referring now to Fig. 11, the main burner casting there shown comprises a pair of side flanges 16 and 17 provided with apertures, as shown, a main generally ovoid wall section 18 (see Fig. 3) defining an open manifold section 19, and generally horseshoe-shaped end flanges 21 provided with openings 22 through which bolts may be inserted for attaching the sections together. At the upper part of the generally ovoid wall section 18 are three upstanding but separated projections 22-22, 23-23 and 24-24, defining channels 26-26 and 27-27. At the lower portion of the generally ovoid wall section 18 is an apertured and threaded boss 28 for attachment of a fuel supply pipe 29.

Assuming, for the purpose of this description, that the individual sections are mounted together to produce a relatively long assembly (the manner of attachment will be referred to later hereinafter), I provide a burner grating running the entire length of the composite singeing burner. This grating comprises a plurality of bar-like grating members 31, each of such a length that, when held at an angle, such as shown in Figs. 2, 6 and 10, will extend substantially to the two inside wall surfaces of the members 23 and lie over and rest on top of the upper surfaces of the members 24. Between each pair of bar-like grating members 31, I provide a pair of grating spacers 32, each of which rests on the top surface of member 24 and has a projection 33 at one corner lying within one of the channels 27. This construction enables the grating members 31 and grating spacers 32 to be wedged tightly together to make a rigid leak-proof structure in which the spacers 32 will be held in proper position, but leaving transverse slots 34 through which combustible vapor and air may be delivered from the manifold 19 for combustion above and outside of the grating slots.

The burner grating assembly is mounted in position by placing alternate grating members and grating spacers in the position shown in Fig. 8 and utilizing wedge members 36 and 37 at opposite ends which have the dual function of clamping the grating members between them and maintaining them at the angle of inclination which they are designed to have. The wedge members 36 and 37 are held in position by end members 38 and 39 in connection with which shims 41 (see Fig. 6) may be employed. The end members are secured in place by means which will be referred to hereinafter.

The burner grating assembly is also held in position in part by flame guards 42 and 43 shown in the drawing as right and left but, in fact, constructed so as to be identical. The flame guards have an apron-like edge 44 through which cap screws 46 are inserted for attachment into threaded apertures in the members 22 of the main burner casting. The base portion of the flame guards then overlie the top edges of the members 22 and 23 and the upper outside edges of the entire burner grating assembly. The flame guards also have an upstanding continuous projection 47 and an internal projecting lip 48. The projection 47 carries a pair of lugs 49 adjacent which are lugs 51 on the main body of the flame guard casting. The function of these parts will be brought out as the description progresses.

One of each pair of flame guards has associ-

ated with it an air inspiration plate 52, the principal function of which will be described hereinafter. This air inspiration plate carries a pair of lug-like projections 53 which engage under the lugs 49 on the flame guard, and the lower inside face of the air inspiration plate 52 rests on top of the lugs 51. A generally angular portion of the air inspiration plate is provided with holes 54 through which bolts 56 extend (Fig. 3), the air inspiration plate resting on spacers 57. The bolts 56 are secured in the flange 16. It will be seen by referring specifically to Fig. 3 that the air inspiration plate 52 is thereby spaced a definite distance from the top surface of the flame guard 42 but has its inside edge spaced from the upstanding projection 47 because of the projections 53.

All of the parts heretofore described are individual to the sections, with the exception of the burner grating which, instead of being made individual to the sections, runs continuously across all of the assembled sections, but which was described in connection with the description of the individual section in order to bring out the relationship of the parts. The remaining portion of the burner assembly may be described as a single unit because the remaining parts are all common to more than one section. The individual sections are secured together in end to end relationship by nuts and bolts 58 which extend through the openings 22 in the flanges 21. It will be seen that the area of the flanges 21, the relative positions of the holes 22 and the cross section of the bolts 58 may all be controlled to obtain any requisite strength where the sections are joined together, thereby enabling one to construct a self-supporting composite singeing burner of any requisite length such as, for example, to singe sheeting or other cloth which is relatively wide.

Between each pair of burner sections, I provide a sealing partition 59 which, in addition to acting as a spacer or partition to make each manifold substantially individual to its own section, also functions as a gasket to prevent leakage between the sections. The sealing partitions 59 are, of course, apertured to pass the bolts 58, but they are also provided with openings 61 and 62 (see Fig. 12) which will be referred to hereinafter.

I have already referred to the end members 38 and 39. These end members are secured to the adjacent flanges 21 of the main burner castings by nuts and bolts 63, and spacers, such as shown in Fig. 12, may be utilized, if deemed necessary, between the flange 21 and the face of the end member 38 or 39, as the case may be.

The end members previously described support the burner grating assembly in assembled position with the burner grating members and grating spacers in intimate relation through engagement of the triangular members 36 and 37. In assembly, one of the end members, such as 38, is mounted in position and, by suitable means, the grating members are stacked and forced in one direction, adding a few additional grating members as the entire assembly is brought up tight, until the proper number of grating members have been introduced. If desired, in place of mounting the end member 38 and wedging the grating members against it, the triangular member 37 may be clamped in position. When the members are properly stacked and assembled, the triangular member 37 being held with a clamp, the end member 38 is placed in position,

and, by selecting the proper number of shims 41, the entire grating may be held firmly by the end members when the nuts and bolts 63 are tightened. This is merely illustrative of a convenient way of producing and assembling the burner grating, but other convenient assembling and anchoring means may, of course, be used. I find that producing a grating in this manner is preferable to cutting slots in a solid bar or moulding slots in a refractory, because, by changing the spacers, the width of the slots may be varied at will and the production and assembly operation is simplified and costs decreased. The materials going into the burner grating are, of course, such as to withstand the temperatures to which they are subjected, as are also the burner guards previously referred to.

For maintaining suitable temperature in the burner assembly, before operations are commenced, I employ a pair of steam pipes 64 and 66 with a fitting 67 (see Fig. 1) at the inner end so that one pipe may be the feed and one the return so as to assure the presence of a plentiful supply of live steam. The pipes 64 and 66, as shown, extend through the openings 61 and 62 in each sealing partition 59 with sufficient snugness so as substantially to produce a seal at these points. In order to seal the manifold, which is adjacent to the end member 39, I provide packing 68 (Fig. 4) which is wedged up into a generally triangular area extending around the pipes 64 and 66 and between the pipes and an enlarged part of the opening through which the pipes extend. Packing nuts 69 threaded on the inside of the end member 39 wedge the packing tightly and produce the necessary sealed joint.

Running continuously along one side of the assembled sections is a supporting plate 71, this supporting plate defining in general an obtuse angle as shown in Fig. 3 and being secured at its lower edge by nuts and bolts 72 to the side flanges 17 of the main burner castings. The supporting plate is also supported at its outer portion by a series of brace rods 13 connected with rings 74 disposed on a transverse supporting rod or pipe 76 which runs the full length of the burner. A shoulder brace rod 77, also carried by each ring 74, engages in special openings provided in the side flange 17 of the main burner casting. At the upper edge of the supporting plate 71, I provide a rounded edge 78, conveniently made by slitting a pipe longitudinally, slipping it over the top edge of the plate 71, and then welding it at 79 as shown. Running continuously across or the length of all of the burner sections and supported on the supporting plate 71 is a relatively heavy layer 81 of refractory or other suitable material designed to absorb heat and act as a radiant heater. As shown, this layer of refractory 81 extends clear over and partly covers the flame guard member 43, and, by its shape, leaves a relatively wide space for the expansion of gases. The edge 78, however, being spaced relatively close to the cloth, for example, on the order of $\frac{1}{8}$ to $\frac{1}{4}$ inch, causes a speeding up of the gases and restricting of air and cold burned gases in positions where they are not desired.

With the brace rods 13 mounted in the position described, it is clear that the rod or pipe 76 acts in part as a support for the entire burner assembly, including the main burner casting. I also provide a second supporting rod or pipe 82 with a series of support rods 83 carried by rings 84 and engaging in the side flange 16. The entire

assembly is also supported in part through the feed pipes 29 which engage in a common manifold (not shown) leading from a suitable oil vaporizer such as that shown in my prior patents heretofore referred to.

The singeing burner assembly is preferably mounted in the general position indicated in Fig. 3, and, to positively position the cloth with respect to the burner, I provide a pair of cloth guides 86. As an important part of my invention, therefore, I include means for positioning the cloth with respect to the burner and the burner with respect to the cloth, although, depending upon the installation, other means than specifically shown may be utilized for accomplishing the purpose.

As a general rule, an installation made for singeing relatively wide cloth will be continued to be used for that purpose. However, at times it may be desirable to limit the burner to a smaller number of sections, and, for this reason, I insert in each one of the feed pipes 29 a valve 87 whereby any one or group of burner sections may be operated.

The general mechanical features, including the structure of the various parts and the manner in which these parts are assembled to produce the singeing burner assembly, are believed to be clear from the preceding description. In using the burner assembly, it is preferably supported on a suitable frame (not shown) of which the rods 76 and 82 form a part. Preferably also, the pipes 76 and 82 are so mounted as to extend across a normal path over which the cloth will travel in its treatment and so that they may be raised and lowered individually or together. That is to say, in mounting the burner in position, it may be supported with the burner firing directly upwardly, as shown in Fig. 3, or it may be fired at an angle to the vertical so that the cloth may be allowed to travel either directly horizontally or directly vertically even, although, of the two positions, the former is preferred. The cloth guides 86 are also supported from a frame so that they can be accurately positioned, and a suitable arrangement, many of which are conventional in textile establishments, is provided for maintaining the cloth taut between the guides so that the position of the cloth with respect to the burner can be adjusted accurately. In general, as previously described, the member 18 should be positioned approximately one-eighth inch from the cloth, and there should also be about one-eighth inch clearance between the extension 41 of the frame guide 42 and the cloth. The remaining parts of the burner will then be automatically positioned because of the structural arrangement. Before starting the singeing operation, steam is preferably passed through the pipes 64 and 66 to preliminarily heat the burner, and the passage of steam through the pipes may be continued, if desired, during operations. The cloth is then threaded into position and the burner lighted, the sequence of operations depending upon the particular operator. However, when the burner is operating at capacity, the cloth should be moving at a relatively rapid rate in the direction indicated by the arrow in Fig. 3.

The functioning of the burner is as follows: The premixed combustible fuel and air passes out through the slots 34 in the burner grating and burn with a definite flame length so that the tips of the flame strike against the cloth or just short of the cloth. Because of the lips 48, a slight turbulence is created which promotes

burning and prevents the flame being forced away from the burner and, therefore, being extinguished, even at high velocity and with a vapor which burns slowly. In other words, a flame retention type of burner is provided. The hot gases, after striking the cloth, pass over the refractory 81 and heat it to substantially a red heat, and the radiant heat from the refractory plus the hot gases preheats the cloth and starts the singeing operation, particularly so far as the surface fuzz is concerned. The movement of the cloth causes a slight suction in the other direction (that is, to the left, looking at Fig. 3), thereby entraining some air at the upper edge of the air inspiration plate 52 thereby drawing air in the path indicated by the arrows at a point very close to the burner flame. This is controlled so that just enough air is admitted to complete the singeing. In addition to overcoming the objections heretofore noted, and securing other advantages suggested hereinabove, the following advantages may be pointed out.

Since the flame from the burner strikes the cloth at an angle, there is no likelihood of burning cloth, even light fabrics. This directioning of the flame also causes the hot gases to flow counter to the direction of movement of the cloth and heat the refractory surface which becomes hot and provides a maximum amount of preheat from the waste gases and also conserves heat for a useful purpose, particularly in that such destructive distillation of surface fuzz as occurs is accomplished in great part in the preheat area. The positioning of the cloth about one-eighth inch away from the flame guard and the outer edge of the burner allows the gases to waste at high velocity with some of the advantages already pointed out. In addition to absolutely controlling the character of the flame, it may be pointed out also that, by the burner construction which I employ, inspiration of cool burned gases is prevented and the clogging of the burner orifices is very effectively avoided. I have already referred to some of the advantages of using the individual sections. To these advantages may be added the fact that, in case of damage, it is only necessary to replace a single section and these sections, made preferably in about six-inch lengths, are made up of separate identical parts which are easily and inexpensively replaced. For example, an entire section may be replaced or an air inspirating plate individual to one section may be replaced or a flame guard may be replaced. Another advantage of the separate sections is that absolute uniformity of flame quality may be maintained entirely across the burner, an effect which could not be so readily attained if a single long manifold were employed.

I have referred in some instances to the types of materials preferably employed, but those skilled in the art understand that the materials throughout in general are selected in accordance with the conditions to which they are subjected and the functions desired. Those parts exposed to heat may be either high grade heat resisting casting, such as in the flame guards, or they may be made of heat resisting stainless sheet metal where forming operations are required, as, for example, in the case of the air inspiration plate or the burner grating members. I wish also to point out that where I refer to the flame, or flame tip, I employ the expression in the conventional sense to mean that operation in which burning of fuel occurs.

I have described my invention in detail to en-

able those skilled in the art to understand and practice the same, and have described the burner as a singeing burner, even though some of its features may be applicable to other uses. The invention clearly is not limited by the description, but only by the scope of the attached claims.

What I claim as new and desire to protect by Letters Patent of the United States is:

1. The method of singeing cloth which comprises producing a combustible mixture of air and oil vapor, burning said mixture in a flame retention type of burner so as to produce a blue substantially neutral flame, passing a strip of cloth continuously in contact with tips of the burner flame, and inspirating a small proportion of air and contacting the cloth therewith at an area immediately adjacent to one edge of the flame.
2. The method of singeing cloth which comprises producing a combustible mixture of air and oil vapor, burning said mixture in a flame retention type of burner, so as to produce a blue substantially neutral flame, passing a strip of cloth continuously in contact with tips of the burner flame, inspirating a small proportion of air and contacting the cloth therewith at an area immediately adjacent to one edge of the flame, and delivering hot products of combustion of said flame along the cloth and in contact with a refractory material in a direction counter to the direction of movement of the cloth.
3. A burner device of the class described comprising a burner, a refractory member at one side of the burner, guide means for cloth to be singed positioned to direct hot gases from the burner into contact with said refractory member, and means for delivering air to the cloth at the side of the burner opposite to that at which said refractory member is positioned.
4. In a cloth singeing burner mechanism, means for producing a substantially neutral flame running transversely of the cloth, a member adapted on being heated to produce a radiant heat, means for causing said neutral flame to impinge said cloth and cause the hot gases therefrom to pass over said member to heat the same, and means permitting discharge of said hot gases around the margin of the burner mechanism, and between the said mechanism and the cloth, and means for introducing a small proportion of air near the burner to complete the singeing of the cloth within the confines of the burner mechanism.
5. A burner of the character described, comprising a plurality of hollow burner sections secured together to produce a relatively long composite structure, spacers between said sections, each section being hollow and having a top opening, a burner grating having a plurality of spaced parallel diagonal slots, said grating extending over said top opening and along all of said sections, flame guards secured to said sections and partly covering said burner grating, said flame guards having inwardly projecting lips whereby to retain a flame resulting from the burning of combustible mixture passing said grating, means to deliver a combustible mixture separately to each burner section, a layer of refractory supported at one side of said burner adjacent one flame guard, and an air inspiration plate opposite thereto and associated with the opposite flame guard.
6. In a cloth singeing burner mechanism, a burner grating, a plurality of burner castings to which said grating is common, said burner cast-

ings comprising individual manifolds, means to secure said burner castings together to produce a composite manifold structure, partitions between said burner castings whereby to produce individual manifold sections, one common to each casting, means to deliver a combustible mixture at substantially uniform pressure to all of said manifold sections, whereby to obtain substantially uniform flame conditions entirely across said burner grating, flame guards at each side of said burner grating, the flame guards being in sections, two sections being common to each burner casting, and an air inspiration plate secured to but spaced from the flame guard sections at one side of the grating.

7. In a cloth singeing burner mechanism, a burner grating, a manifold through which a combustible mixture of air and vaporous fuel is adapted to be delivered to the burner grating, said combustible mixture adapted to be maintained at uniform pressure, whereby substantially uniform flame conditions may be maintained substantially entirely across the burner grating, flame guards at each side of the burner grating and an air inspiration plate secured to but spaced from the flame guard at one side of the grating.

8. In a cloth singeing burner mechanism, a burner grating, a manifold through which a combustible mixture of air and vaporous fuel is adapted to be delivered to the burner grating, said combustible mixture adapted to be maintained at uniform pressure, whereby substantially uniform flame conditions may be maintained substantially entirely across the burner grating, flame guards at each side of the burner grating, an air inspiration plate secured to but spaced from the flame guard at one side of the grating, a refractory element supported at the opposite side of the burner grating to that occupied by the air inspiration plate, the cloth being adapted to travel in a direction to pass in order the refractory element, tips of the flame projecting from between said flame guards, and the air inspiration plate, and guides to hold said cloth in spaced relation to said refractory element and air inspiration plate, whereby to permit exhaust gases to pass over said refractory element to maintain it in heated condition, and substantially to exclude air therefrom.

CHARLES A. FRENCH.
